UNITED STATES PATENT OFFICE.

HERMAN L. GREVE, OF NEW YORK, N. Y., ASSIGNOR TO INTERNATIONAL MAILING
TUBE & WRAPPER COMPANY, A CORPORATION OF NEW YORK.

MAILING-ENVELOP.

1,160,280.

Specification of Letters Patent. Patented Nov. 16, 1915.

Application filed June 29, 1915. Serial No. 36,920.

To all whom it may concern:

Be it known that I, HERMAN L. GREVE, a citizen of the United States, and a resident of New York city, borough of Brooklyn, in the county of Kings and State of New York, have invented certain new and useful Improvements in Mailing-Envelops, of which the following is a specification.

This invention relates to mailing envelops, particularly to a form of envelop which may with equal advantage be made in large or small sizes out of flexible or stiff paper.

In the forms of envelops hitherto used for mailing third class matter, especially in the larger sizes, it has almost always been found necessary to use some special form of fastener which had to be attached to the paper. Such a fastener not only is comparatively expensive but renders it obvious that the envelop is unsealed, making it at once apparent that the matter sent is not first-class mail.

The present invention has for its object to dispense with the use of the separate fastener, giving the appearance of a sealed envelop, whereas the envelop is really unsealed and thus may be transmitted under third class mail matter rates.

In the drawings illustrating a few of the various forms in which my invention may be embodied, Figure 1 is a plan view of one form showing the envelop open. Fig. 2 is a similar view showing the envelop closed. Fig. 3 is a perspective view illustrating the parts in intermediate position assumed when the flaps are being folded to close the envelop. Fig. 4 illustrates a modified form with two sealing points instead of one. Fig. 5 illustrates a further form in which the body of the envelop is folded. Fig. 6 is a view similar to Fig. 5 partly unfolded. Figs. 7 and 8 illustrate forms adaptable for stiff paper.

Referring in detail to the drawings, particularly to Figs. 1, 2 and 3, my improved envelop has extending from the front and back portions thereof at its mouth contiguous flaps 10 and 11 which are preferably tapering in outline and their lateral edges 12 and 13 respectively converge correspondingly. The edges 12 of the flap 10 preferably converge more abruptly than the edges 13 of the flap 11, thus forming an overlapping portion on the flap 11 which extends past the edges of the flap 10 and may be readily manipulated when the envelop is

closed. If desired, the flap 10 may, at some point adjacent to its extremity, be tapered still more abruptly to come to a vertex 14. However, it will be understood that the extremity may be left blunt instead of coming to a vertex.

At a suitable point on the back of the flap 10, preferably adjacent to the vertex 14, a comparatively small area 15 is gummed and the flap 11 is formed with a corresponding cut-out 16, so as to clear the gummed area 15.

When the envelop is to be closed, the flaps are together folded over along an intermediate line 17-18 as indicated generally in Figs. 1 and 3. The gummed portion 15 is moistened and then the flaps are folded over again into the position illustrated in Fig. 2, along the line 22 so that the gummed area 15 adheres to the body of the envelop, thus holding the flaps in locked position. It will be seen that the cut-away 16 divides the flap 11 into two sections or tongues 19, 20, these tongues being securely held beneath the flap 10 after it is attached to the envelop body.

When it is desired to open the envelop, it is merely necessary to insert a finger under the edges 13 to pry the tongues 19, 20 from their folded position under the flap 10. The flexibility of the material will be sufficient to permit this operation to be carried out very readily without tearing the envelop or breaking the seal of the gummed portion of the flap 10 against the body of the envelop. In case the material is quite flexible, the cut-away portion 16 may be so shaped as to form horns 21 which partly surround the gummed area 15 and serve to securely hold the sections 19 and 20 under the flap 10 until they are removed by the manipulation above explained.

In the modified form illustrated in Fig. 4, provision is made for a wider mouthed envelop. The flap 30 may thus converge to a blunt edge 31 and the flap 32 may be formed with two cut-outs 33 and 34 about two gummed areas 35 and 36 on the back of the flap 30. Otherwise, the construction is the same as that of the envelop first described.

In the further modified form illustrated in Figs. 5 and 6, the flaps 40 and 41 are made shorter so as to fold only once, the second fold being made in the body of the envelop along the line 42. The portion 43 which is folded over thus has its marginal edges

closed instead of open as in the forms previously described. This makes the closure of the envelop tighter and renders it suitable for holding a granular or powdered substance.

In the further modified form illustrated in Fig. 7, a construction is shown which is particularly adapted for stiff paper. Thus, the flap 50 is made so that it can be folded over on itself, and on the back thereof adjacent its extremity is provided a gummed space 51. The flap 52 is formed with a cut-away portion, dividing the extremities thereof into two tongues 53 and 54 and on each side of the gummed area 51. However, by reason of the fact that the material is stiff, the inturned horns of the other forms described are omitted and instead of tongues are formed with diverging edges 55 and 56 at the cut-away. Thus, the tongues may be readily unfolded when the envelop is closed without breaking the seal, and to facilitate this, the tongues are preferably formed with corrugations 57 which render the same more flexible.

The form illustrated in Fig. 8 is substantially similar to that in Fig. 7 but with the corrugations omitted. This form is adaptable for paper which is not so stiff as that which may be used in the form in Fig. 7.

It will be noted that according to my improved construction the flap when closed is reinforced as it forms a plurality of layers and thus will not tear as readily as in the forms of envelopes of the usual construction.

It will be understood that various further modifications may be made without departing from the scope of the invention as defined in the accompanying claims.

Having thus described my invention, I claim as new and desire to secure by Letters Patent:

1. A mailing envelop comprising a body having a front and back portion, flaps extending from said front and back portions at the mouth of the envelop, one of said flaps being provided with a gummed area adjacent its extremity and the other of said flaps being formed with a cut-away portion opposite said gummed area whereby the gummed flap may be sealed to removably hold the second flap in place.

2. A mailing envelop comprising a body having a mouth, contiguous flaps extending from the body at the mouth, one of said flaps being formed with a gummed area and the

other of the flaps being formed with a cut-away portion about the gummed area whereby the first flap may be sealed to the body and removably hold the second flap thereto. 60

3. A mailing envelop comprising a body portion formed with a mouth, a pair of flaps extending from the body at the mouth, one of the flaps being provided adjacent its extremity with means for attaching the same 65 to the body of the envelop and the other of the flaps being formed with a cut-away portion about said attaching means dividing the same into a plurality of sections removably held by the first mentioned flap against the 70 body of the envelop.

4. In a mailing envelop, a body portion having a mouth, a pair of flaps extending from the body of said mouth, the first of said flaps being provided at its extremity with 75 means for attaching the same to the body of the envelop, a second flap being formed with a cut-away portion about said attaching means dividing the second flap into a plurality of sections, the lateral edges of the 80 second flap overlapping the edges of the first flap whereby said second flap may be readily manipulated to remove the sections from beneath the first flap without detaching the first flap from the body. 85

5. A mailing envelop comprising a body portion formed with a mouth, a pair of flaps extending from the body at the mouth, one of the flaps being provided adjacent its extremity with means for attaching the same 90 to the body of the envelop and the other of the flaps being formed with a cut-away portion about said attaching means dividing the same into a plurality of sections having projecting portions partially surrounding said 95 attaching portion, said sections removably held by the first mentioned flap against the body of the envelop.

6. A mailing envelop comprising a body portion formed with a mouth, a pair of flaps 100 extending from the body at the mouth, said flaps being adapted to be folded twice to close the envelop, and means for sealing the interior flap to the body of the envelop to removably hold the exterior flap thereto. 105

Signed at New York city, in the county of New York and State of New York, this 22nd day of June, A. D. 1915.

HERMAN L. GREVE.
